DESIGN FOR A SLEEPING BAG OR SIMILAR ARTICLE

Bertha C. Rose, Boston, Mass., assignor to Rose-Derry Company, Newton, Mass., a corporation of Massachusetts

Application December 4, 1943, Serial No. 111,901

Term of patent 14 years

(Cl. D92—2)

To all whom it may concern:

Be it known that I, Bertha C. Rose, a citizen of the United States, residing at Boston, in the county of Suffolk and State of Massachusetts, have invented a new, original, and ornamental Design for a Sleeping Bag or Similar Article, of which the following is a specification, reference being had to the accompanying drawing, forming part thereof.

In the drawing,
Fig. 1 is a plan view of a sleeping bag showing my new design; and
Fig. 2 is a side elevational view thereof.

I claim:

The ornamental design for a sleeping bag or similar article, substantially as shown.

BERTHA C. ROSE.
